CLAIM

The ornamental design for a wide mouth beverage container, as shown and described.

DESCRIPTION

FIG. 1 is a top perspective view of a wide mouth beverage container showing my new design.

FIG. 2 is a front perspective view thereof.

FIG. 3 is a rear view thereof.

FIG. 4 is a left side view thereof.

FIG. 5 is a right side view thereof.

FIG. 6 is a top plan view thereof; and,

FIG. 7 is a bottom plan view thereof.

The two innermost broken lines and areas within them in FIG. 7 depict portions of the wide mouth beverage container that form no part of the claimed design. The outermost broken line in FIG. 7 depicts a boundary to the claim and forms no part thereof.
